UNITED STATES PATENT OFFICE.

ALEXANDER McNAB, OF BRIDGEPORT, CONNECTICUT.

REVERSING RUDDER.

Application filed December 8, 1925. Serial No. 74,074.

This invention relates to the control of navigable vessels and particularly to power driven vessels fitted with a reversing rudder known as the McNab-Kitchen rudder.

5 The object of the invention is to provide a simple and efficient control mechanism which may be readily adapted to or combined with any type of stern and either with outboard motors or inboard motors.

10 A further object of the invention consists in arranging the control mechanism in a minimum space while maintaining full strength of the parts so that the mechanism may be mounted in any convenient position.

15 A further object of the invention is to arrange the parts in a small and compact casing serving as a protective and grease retaining housing.

20 A still further object of the invention is to provide a reversing rudder control having means by which the setting of either or both the steering and rudder setting may be readily locked in adjusted position and as readily released when another setting or free manœuvring is desired.

25 A still further object of the invention is to construct and assemble the various parts constituting the control so as to be readily demountable for purposes of adjustment or renewal.

30 Various other features of the invention will hereinafter appear and be specifically pointed out in the appended claims.

Reference is now directed to the accompanying drawings in which a preferred embodiment of the invention is illustrated by way of example, but it will of course be understood that the invention is not limited in its scope to the form illustrated but only as defined in the appended claims. Corresponding parts are indicated by the same reference numerals in the various figures of the drawings, in which:—

35 Figure 1 illustrates an outboard motor of well known make fitted with the McNab-Kitchen reversing rudder controlled by the mechanism forming the subject of the present invention and illustrating the adaption of the control to an outboard motor clamped to a boat with a transom stern.

40 Figure 2 illustrates the control mechanism used with an inboard motor in a boat having an overhung stern;

45 Figure 3 illustrates the invention applied to a boat having an inboard motor and transom stern.

Figure 4 is an enlarged view of the control mechanism mounted in its housing and showing the locking adjustments for both steering and rudder setting; 60

Figure 5 is an enlarged view in side elevation of the mechanism arranged in its housing, one-half of said housing being removed;

Figure 6 is a sectional elevation on line 5—5 of Fig. 4 looking in the direction of the arrows. 65

Figure 7 is an enlarged inverted plan view on the line 7—7 of Fig. 5 looking in the direction of the arrows.

The McNab-Kitchen rudder is well known 70 in marine engineering and is particularly widely fitted to small craft plying in narrow waters. It consists essentially of two semi-circular plates pivoted together and embracing the propeller. The blades are mounted on separate nested shafts and shaped to enable the rear edges when brought together to form a complete closure behind the propeller, the range of setting of the rudder enabling the semi-circular blades to be set in any position 75 from approximately parallel relation with each other through any intermediate position to a close fitting of the plates along their rear edges. In addition both plates may be swung together about their vertical axis for steering in the usual manner. The shape of the blades illustrated in the drawing has been found particularly advantageous since it provides a balanced rudder. The adjustable setting of 80

the blades relatively to one another for manœuvring purposes enables any range of speed from full ahead to full astern to be obtained without varying the revolutions of the propeller or its direction of rotation. In addition the turning of the boat on a vertical axis 85 passing approximately through the center of its length is obtainable by putting the rudder hard to star-board or port when in fully closed position. While by adjusting the setting of the rudder plates so that the reaction 90 of the water forced between the rudder plates is balanced by that of the water deflected forwardly by the blades, the boat or vessel can be held stationary while the propeller is revolving at normal speed. 95

100 It will be realized that the manœuvring power given by the McNab-Kitchen rudder is extremely valuable, particularly where manœuvring in a restricted space is necessary and for this reason large numbers of 110 these rudders have been fitted to outboard motors. For this reason the invention has

been illustrated as applied to small boats but it will be understood that both the rudder and the control mechanism therefor herein described are applicable to craft of any size in 5 tonnage, though in large vessels it is advisable to provide power means for operating such control mechanism.

The control mechanism illustrated is mounted at the head of nested rudder stems 10 operating the rudder plates, one plate of the rudder being mounted upon a tubular stem 1 through which the stem 2 of the other rudder plate passes. Mounted at the upper ends 15 of the inner and outer stems are collars 3 and 4 provided with gear teeth 5 which are brought to the same horizontal level. In the particular construction illustrated, these gear teeth project outwardly at an angle of approximately 45 deg. from the collars, but this is 20 of course merely a preferred form since the teeth or serrations could be arranged to extend vertically or horizontally if preferred.

A tiller socket member 6 is provided with a yoke member 7 extending transversely of 25 the rudder stems and carrying a toothed segment 8 at each extremity meshing with the gear teeth 5 on the rudder stem collars. This tiller socket member 6 is capable of to and fro movement in a vertical plane as well as 30 the usual movement in a horizontal plane for ordinary steering. The parts just described are mounted in a small casing 9 providing a bearing for the socket member 6 and for the nested rudder stems. It is very important 35 that no appreciable force should be applied to the rudder plates after they have come into contact with each other as serious distortion of the plates may be caused. The range of movement of the parts within the 40 casing is limited in the illustrated construction, in one direction by a flange 10 on the yoke member 7 coming against the rudder stems and in the reverse direction by said flange 10 coming against the inside of the 45 casing, the range of movement being sufficient to swing each rudder plate through an angle of approximately 45° when the tiller is moved from extreme downward to extreme upward position. Movement of the tiller to 50 right or left of course swings both stems and blades equally in the same direction for steering in the usual manner.

The construction of the housing or casing 9 is such as to enable it to be readily dismounted 55 but to provide a grease retaining chamber when assembled. The casing comprises two halves held in position by only three bolts 11, 12, 13. Of these bolts 11 forms the pivot for the socket and yoke member, in addition 60 this bolt is capable of being readily tightened up to lock the socket and yoke member 6 in adjusted position through lever 20. The casing is held at its lower end by bolts 12, 13, 65 serving to clamp in position a phosphor bronze bearing sleeve 14 which extends be-

low said casing sufficiently to be embraced by a bracket 15. This bracket 15 serves to connect and brace the rudder stems to the vertical propeller shaft of an outboard motor, or to the stern, if an inboard motor is being used, the rudder being given a further point of support by the bottom pivot bearing 16 carried by the propeller protecting skeg 17 in the usual manner. The bracket 15 serving 70 to hold the rudder in position on the boat or outboard motor also serves as a lock, for this purpose it is split and furnished with a quick threaded bolt 18 and thumb nut 19 enabling the projecting portion of the bushing 14 and thereby the casing 9 to be readily 80 locked in any desired setting. It is found that the metal of the casing possesses sufficient spring to enable the clamping of the tiller socket member to be effected without permanently distorting the casing, slackening 85 back of the pivot bolt member enabling the casing to spring back to normal position leaving the socket member completely free. The socket member pivot bolt is provided at its end with a quick feed thread taking into 90 a nut 20 held from turning by fitting between raised ribs 21 cast on the casing. Preferably hard fiber washers 22 are arranged between the casing and socket member.

It is believed that the operation of the 95 steering control will be readily understood from the foregoing description taken in conjunction with the drawings.

The manipulation of the tiller serves to control both the direction ahead or astern, and the speed of the boat, both these functions being effected either independently by an up and down or side to side movement of the tiller or simultaneously by moving the tiller both horizontally and vertically.

The advantages of this extremely light and simple mechanism will be appreciated by all those conversant with the use of small boats, particularly where it is desired to handle other gearing such as fishing tackle or guns, the 100 readily locking means enabling the boat to be held on a desired course and at any desired speed without attention.

It will be seen from the different forms of stern shown fitted with the rudder control 105 that the gears and gear casing may be arranged wherever convenient, this being possible owing to the very compact arrangement of the gears and consequent small size of the casing 9. When the rudder stems are brought 110 through a deck so that the bracket 15 is not required, any suitable form of bearing enabling the clamping of the projecting sleeve 14 may be provided as will be understood. The casing 9 may be mounted on the rudder 115 stems so that the tiller socket projects either forwardly or rearwardly, the advantage of this is that the tiller may, if desired be bent over an outboard motor arranged in the usual 120 position. If desired stops to limit the side to 125

side movement of the rudder may be formed on the casing, said stops engaging with a suitable part such as the supporting bracket 15.

While a preferred embodiment of the invention has been described various modifications thereof can of course be readily effected and it is not desired to restrict the invention otherwise than as defined in the appended claims.

16. What I claim is:

1. A reversing rudder attachment adapted to cooperate with the power equipment of a navigable vessel, including a rudder having two substantially semi-circular pivoted plates 15 adapted to be moved from approximate parallelism to each other into position contacting with each other along their trailing edge, nested stems connected to said rudder plates, split bearing means associated with the rudder mechanism and locking means acting to close said split bearing means to hold said rudder plates in a desired setting relatively to each other and in a desired angular setting relatively to the longitudinal axis of the 25 vessel.

2. A reversing rudder attachment as claimed in claim 1, having actuating mechanism for the nested stems arranged at the upper end thereof, said mechanism including a 30 member mounted in a split bearing and a second split bearing for said nested stems, and locking means associated with each of said split bearings whereby said rudder plates may be locked against movement relatively to each 35 other and the rudder as a whole may be locked against movement relatively to the longitudinal axis of the vessel.

3. A reversing rudder attachment adapted to cooperate with the power equipment of a 40 navigable vessel comprising a tiller socket member, a yoke member operated by the actuation of said tiller socket, a rudder comprising two substantially semi-circular pivoted plates adapted to be moved from approximate 45 parallelism to each other into position contacting with each other along their trailing edge, nested stems connected to said rudder blades, and collars mounted at the upper ends of said stems, gear segments carried by 50 said collars and gear teeth on said yoke member meshing with said first mentioned gear segments, movement of the socket member being transmitted through said gearing to the 55 pivoted blades.

4. A reversing rudder attachment adapted to cooperate with the power equipment of a 60 navigable vessel a tiller socket member, a yoke member operated by the actuation of said tiller socket, a rudder comprising two substantially semi-circular pivoted plates 65 adapted to be moved from approximate parallelism to each other into position contacting with each other along their trailing edge, nested stems connected to said rudder blades, actuating means mounted at the upper ends of

said nested stems and operated by said yoke means, and a casing housing the actuating parts said casing providing a pivotal bearing for the tiller socket member and a bearing for said nested stems.

5. A reversing rudder attachment adapted to cooperate with the power equipment of a 70 navigable vessel comprising a tiller socket member, a yoke member operated by the actuation of said tiller socket, a rudder comprising two substantially semi-circular pivoted plates 75 adapted to be moved from approximate parallelism to each other into position contacting with each other along their trailing edge, nested stems connected to said rudder blades, actuating means mounted at the upper end of said nested stems and operated by said yoke means, and a casing housing the actuating parts, the movement in one direction of said yoke member being limited by a 80 part thereof contacting with the casing and in the other direction with the rudder stems.

6. A reversing rudder attachment adapted to cooperate with the power equipment of a 85 navigable vessel comprising a tiller socket member, a yoke member operated by the actuation of said tiller socket, a rudder comprising two substantially semi-circular pivoted plates 90 adapted to be moved from approximate parallelism to each other into position contacting with each other along their trailing edge, nested stems connected to said rudder blades, actuating means mounted at the upper ends of said nested stems and operated by said yoke means and a casing housing the 95 actuating parts and providing a pivotal bearing for the tiller socket member, the movement of said yoke member being limited by a part thereof contacting in one direction with the casing and in the other direction with the 100 rudder stems the pivotal bearing for the tiller socket member comprising a bolt provided with an actuating lever at one end and projecting at its other end beyond the said casing, the projecting end of the bolt being 105 provided with a threaded portion taking into a threaded part carried by said casing.

7. A reversing rudder attachment adapted to cooperate with the power equipment of a 110 navigable vessel as claimed in claim 6, in which said threaded part comprises a nut held from rotation by projecting ribs cast on the exterior of the casing.

8. A reversing rudder attachment adapted to cooperate with the power equipment of a 115 navigable vessel comprising a tiller socket member, a yoke member operated by the actuation of said tiller socket, a rudder comprising two substantially semi-circular pivoted plates 120 adapted to be moved from approximate parallelism to each other into position contacting with each other along their trailing edge, nested stems connected to said rudder blades, actuating means mounted at the upper ends of said nested stems and oper- 125

ated by said yoke means, and a casing containing the parts, the movement of said yoke member being limited by a part thereof contacting in one direction with the casing and in the other direction with the rudder actuating members, said casing comprising two halves held together at its upper end by a bolt serving as a pivotal connection for said socket member and at its lower end by two bolts serving to clamp in position a sleeve bearing for said rudder stems, said casing forming a container adapted to contain grease or other heavy lubricant.

9. A reversing rudder attachment as claimed in claim 8 in which the sleeve bearing for said rudder stems, clamped in said housing, projects beyond said casing, a brace to hold said rudder mechanism in position to brace said rudder mechanism and formed as a split bearing, embracing the projecting portion of said bushing, and means for readily closing said split bearing to lock said elongated bushing in any desired setting.

In testimony whereof I have affixed my signature.

ALEXANDER McNAB.
